Fig. 11.

Fig. 7.

A hand-drawn diagram of a pulley system. A horizontal line represents a string that is attached to a mass labeled 'm3' on the left. The string passes over a pulley, and a tension force 'T' is indicated at the point where the string leaves the pulley. The string then continues to the right, with a portion of it being shaded with vertical lines.

REGISTER

George B. Dunn, Miami, Fla.

Application July 30, 1934, Serial No. 737,668

9 Claims. (Cl. 235—32)

This invention appertains to new and useful improvements in registers and is a continuation in part of my co-pending application Serial No. 628,397, filed August 11, 1932.

5 An important object of the present invention is to provide a register particularly adapted for use on public conveyances whereby coins of different sizes and denominations can be deposited and counted before handling of the same by the 10 operator of the conveyance.

Another important object of the present invention is to provide a register wherein means is provided whereby the operator is apprised of the 15 number of coins inserted and the value thereof by a novel annunciator.

Other important objects reside in the positive 20 action of the device, the substantial fool-proof character of its mechanism, and its durable construction which will eliminate the necessity of making frequent repairs.

Other objects will become apparent as the following specification proceeds.

In the drawings:

Figure 1 represents a side elevational view of 25 the machine.

Figure 2 is an end elevational view of the machine.

Figure 3 is a fragmentary side elevation of the 30 machine showing the opposite side from that shown in Figure 1.

Figure 4 is a transverse sectional view through the machine showing the position of the mechanism with a coin about to be inserted.

Figure 5 is a transverse sectional view through 35 the machine showing the mechanism in position with a dime about to be discharged.

Figure 6 is a transverse sectional view showing the mechanism in position carrying a nickel towards the nickel discharge opening.

40 Figure 7 is a transverse sectional view showing the mechanism with a nickel in the act of being discharged.

Figure 8 is a transverse sectional view through the mechanism showing the plate and lug for re- 45 turning the coin handling disk to re-set position.

Figure 9 is a transverse sectional view through the mechanism showing the nickel-outlet closure operating means.

Figure 10 is a fragmentary transverse sectional 50 view showing the spring means for the reversing pawl.

Figure 11 is an exploded view showing the drive disk and follower disk and associated washer and nut.

55 Figure 12 is a transverse sectional view through

the mechanism showing the equalizing springs for the vacuum control valve trip shaft.

Figure 13 is a transverse sectional view through the machine showing the vacuum valve actuating mechanism.

5 Figure 14 is a transverse sectional view similar to that shown in Figure 13, but with the valve tripped to operating position.

Figure 15 is a fragmentary side elevational view of the follower disk.

10 Figure 16 is a fragmentary side elevational view of the stationary partition showing the pinion driving spring.

Figure 17 is a sectional view taken substantially on line 17—17 of Figure 16 with the pinion 15 mounted in place.

Figure 18 is a perspective view of the vacuum valve trip shaft.

Figure 19 is a perspective view of the rack unit 20 for the valve reversing mechanism shown in Figure 13.

Figure 20 is a perspective view of the rockable spring tensioner.

Figure 21 is a fragmentary detailed sectional view taken substantially on line 21—21 of Figure 9.

Figure 22 is an elevational view of the nickel outlet closure.

Figure 23 is a transverse sectional view through the mechanism showing the annunciator and its 30 operating mechanism with parts broken away.

Figure 24 is an exploded view showing perspective the several parts of a clapper assembly of the annunciator assembly shown in Figure 23.

Figure 25 is a transverse sectional view disclosing the follower disk, the register, and the means for operating the register.

Figure 26 is a longitudinal sectional view through the entire mechanism.

Figure 27 is a perspective view of the sheet 40 metal jacket for the mechanism.

Figure 28 is a transverse sectional view through the vacuum chamber of the machine.

Figure 29 is a fragmentary sectional view taken substantially on line 29—29 of Figure 28.

45 Figure 30 is an elevational view of the valve element.

Figure 31 is a fragmentary sectional view taken substantially on line 31—31 of Figure 28.

Figure 32 is a sectional view taken substantially on line 32—32 of Figure 28.

50 Figure 33 is a side elevational view of the vacuum chamber piston.

Referring to the drawings wherein like numerals designate like parts, it can be seen in 55

Figure 1, that the machine is preferably supported by an upright 5 suitably secured to a floor base (not shown). A block 6 in the form of a saddle has a threaded recess or socket therein for receiving the threaded upper end of the upright 5. The casing 7 encompasses the saddle 6 and has an opening in the bottom thereof for receiving the upright 5. One end of this casing 7 is constructed to provide a money box 8 having a window 9 in the side thereof and a swingable bottom 10, the bottom 10 being on the hinge 11 and provided with a finger engageable member 12 depending from the lower side thereof. A lamp socket 13 is mounted on the saddle 6 and receives a bulb 14 which supplies illumination for the money box 8. Conductors in connection with the socket 13 may extend through the hollow upright 5.

The mechanism proper includes an elongated cylindrical shell 15 which is provided with a sheet metal jacket 16 for the purpose of concealing quite a number of the screw heads visible on the outer side of the shell 15. This jacket 16 wraps around the cylinder shell 15 in substantially the manner shown in Figures 1 and 2, the same being provided with openings therein registering with similar openings in the shell 15 to accommodate the vacuum line fitting 17 (see Figures 1 and 26), the locking pin 18, the coin slot plate 19, and the vent 20 allowing the atmosphere to the interior of the cylinder just inside of the end plate 21. The opposite end of the shell 15 is provided with a perforated end plate 22.

In order to secure the shell 15 in place on the saddle 6, a band 23 is hingedly connected at one end as at 24 to one side of the casing 7 and extends over the shell 15 and its jacket 16. The free end of the band 23 is provided with a cam lever 25. This cam lever is connected to the adjacent end of the band 23 by a spring device consisting of U-shaped members 26-26 on the lever 25 and adjacent end of the band 23 between the leg portions of which extend extensible cord springs 27-27. A boss 28 on the shell 7 (see Figure 2) has a groove on the bottom side thereof with which the cam end of the lever 25 can be engaged when the band is properly disposed over the shell and by pushing inwardly the lever can be thrown against the shell 7 as shown in Figure 2 to tensionally retain the band in position over the shell.

The mechanism inside of the shell 15 includes the vacuum responsive assembly at one end of the shell 15, while within the opposite end of the shell 15 is located the annunciator 30 along with the register generally referred to by numeral 31.

Within the shell 15 and intermediate the ends thereof is the assembly of disks for direct association with the coins deposited, this assembly being generally referred to by numeral 32.

It will be observed that the assembly of disks consists of the follower disk A, the coin drive disk B, the stationary partition C, the unit of three disks D, and the fixed disk E.

It will be observed that the coin slot plate 19 has a coin slot 33 therein for registering with corresponding slots in the shell 15. The coin drive disk is provided with a hub 34 having a pintle extension 35 for disposition axially through the disk A. A nut 36 on the pintle 35 maintains the washers 37 against the follower disk A. The drive disk B is provided with the drive pin 38 which is provided with the reduced extension or rib thereon for riding disposition in the channel-

way 39 of the disks of the unit D opposed to the partition C. (See Figure 9.)

As is clearly shown in Figure 11, the drive disk B is shown with a concentric slot 40 terminating at one end in an enlarged opening 41. This enlarged opening 41 simply serves to facilitate assembling of the disk C with the disk A by inserting the head 42 carried by disk A which is of wedge shape through the opening 41 so that its neck portion 43 can engage into the slot 40. 10

The drive pin 38 of the disk B extends through the slot 44 of the partition C, while the follower wedge 42 has its neck riding in the slot 45 of the partition C, it being observed at this point that the partition C is separated from the multiple 15 plate unit D by a ring 46, thus defining a coin passageway along which the coins can travel as in the dotted line position shown in Figures 5, 6, and 7. In this manner, both the drive pin 38 and the follower wedge 42 ride in the coin pas- 20 sageway.

Rotatably mounted on the hub 34 and within this coin passageway is a rotary collar 47 which, as shown in Figure 7, has a peripheral cutaway portion 48 to accommodate the pinion 49 and a 25 peripheral cutaway portion 50 into which a nickel must engage as shown in Figure 4 if it is to be moved toward the nickel outlet 51. The primary function of this collar 47 is to provide cam means for lifting the closure 52 from the nickel outlet 51. This closure 52 as shown in Figure 9 and also in Figure 21 is provided with a plate extension 53 which operates between the two outside plates of the three-plate unit D, one of the outside plates being provided with a radially dis- 35 posed slot 54 therein in which the pin 55 on the plate extension 53 is slidable. This pin 55 extends through the eccentric grooveway 56 of the collar 47.

As is clearly shown in Figure 9, a pin 58 ex- 40 tends laterally from the collar 47 and through the registering slots 59 of the disk assembly D to protrude in the path of the return plate 60 which is provided with a lug 61 thereon engageable with the said pin 58. This plate 60 is se- 45 cured by a screw 62 to one end of the hub 34. A stud 63 on the stationary disk E projects into the grooveway 64 of the disk assembly D as shown in Figure 8.

As the insertion of the coin through the coin 50 slot 33 effects the operation of the mechanism by controlling the vacuum line to the vacuum chamber 29, a discussion of the details associated with this function will now be given.

In the first place, it will be understood that 55 the aforementioned ring 46 is provided with a slot therein with which the coin slot 33 registers and slidable in this ring slot is the slide extension 65 which is adapted to close the slot 33 when a coin is in progress through the coin 60 passageway, or partly closed as in Figure 4, the re-set position of the details. This extension 65 is on the slide plate 66 which is provided with a small section of teeth 67 along one edge and a rack 68 along its opposite edge. A notch 69 is located in the first mentioned edge of the slide plate 66 at each end of the toothed section 67 and it will be observed that the swingable catch 70 is engageable with the teeth 67 and capable of reversing itself in the notches 69, as 70 is clearly shown in Figure 10. The catch 70 is on a short shaft 71 having a small lever 72 and a spring extending from the free end of the lever to connect to an anchor 73. The pawl or catch 70 will serve to prevent the slide plate 66 75

from returning without completing a full stroke regardless of in which direction it is moving.

Numeral 74 represents a stop pin on the disk C with which the spring pressed and pivotal member 75 on the slide plate 66 is engageable. It will be observed that the slide plate 66 is guided by pins 76—76 riding in the slots 77—77 of the disk C.

The aforementioned gear 49 as shown in Figure 17 is on a short shaft 78 journaled through the disk C, the disk C being provided with a circular pocket 79 having a cover 80. The cover or closure plate 80 serves as a bearing for the gear 49 and also to maintain the spring 81 confined in the pocket 79. One end of this spring 81 is anchored as at 82 while its other end is connected to the shaft 78 as shown at 83. Screws 84 can be driven into the threaded openings 85 in the disks C so as to engage the cover plate 80 and secure the same in place over the bracket 79. It can now be seen that when the slide 65 is in the position shown in Figure 7, the tension of the spring 81 is substantially spent. When the slide 66 is in the position shown in Figure 4, the spring is under tension as it will be when the coin is being inserted through the slot and the slide pushed all the way back where the pawl 70 reverses in one of the notches 69 so that when the coin is entirely in the coin passageway and the driving pin 38 starts to drive the coin down the passageway, the slide will snap back to the fully closed position shown in Figure 6.

It will be observed that the insertion of the coin is what controls the operation of the vacuum responsive mechanism and in this connection an elongated shaft 85 is employed, the same being provided at one end with a small lever 86 which is engageable by the teat 87 on the slide 66, while at the opposite end of the shaft 85 is located a trip arm 88 for tripping the valve mechanism generally referred to by numeral 89 in Figure 13.

It will be observed in Figures 12 and 18 that the shaft 85 is provided with a cross arm 90, each free end terminating in an eye 91 and that a spring member 92 at opposite sides of the shaft each has one end anchored as at 93 and its other end connected to the eye of the corresponding arm end. Thus the shaft 85 is normally maintained in the re-set position by reason of its equalizing spring arrangement.

The shaft 85 extends through a tube 94 which in turn extends through the vacuum chamber 95, this chamber forming a unit in one end of the shell 15. The chamber is secured in place by one or more screws 96. A block 97 is located in the chamber 95 and is provided with a protuberance 98 extending through an opening in the end plate 99' of the chamber 95. In this protuberance are the outer ends of ducts leading through the block 97 to opposite sides thereof and an outlet for the vacuum duct 99. The valve element 100 which is rotatably mounted on the protuberance 98 and tensionally urged against the same by the spring 101 has the communicating channel 102 thereon and the two openings 103 and 104 whereby the interior of the chamber at one side or the other of the body 97 can be opened to the atmosphere. Numeral 105 represents an arm on the valve element 100, which arm is provided with a foot portion 106 as shown in Figure 13.

Journaled through the chamber 95 is the core 107 which has its end portions extend through

the ends of the chamber 95 in the manner substantially shown in Figure 26, with one end bifurcated and opposed to the bifurcated and reduced end portion 108 of the hub 34 (see Figure 26) so that the key 109 can be employed for connecting these two elements in driving relation. The other end of the core 107 is provided with the pinion gear 110 secured thereto by a screw 111.

It will be observed that the innermost edge 10 portion of the block 97 is drilled with a plurality of openings into which grease can be packed, while packing strips 111—111' are secured to opposite sides thereof so as to bear against the core 107. This edge portion of the block 97 is 15 concaved to form a seat for the core 107. The piston assembly which is carried by the core 107 consists of the plate 112 extending radially from the core 107. Side plates 113—113 are secured to opposite sides of this plate 112 and serve to secure the leather plates 114—114 in position against the plate 112 so that their outer ends will flex against the inner side of the chamber 95. The plate 112 terminates inwardly of the leather packing plates 114 as shown in Figure 28. The piston plate 112 is transversely and longitudinally bored to form openings for grease packing. The space between the leather plates 114 is provided with a filler 115. A spring bracket 116 on one side of the piston carries a packing plate 30 117 and this serves as a valve against the opening on the opposed face of the block 97 when the piston is around to this position.

The valve manipulating mechanism 89 involves a plate 118 suitably secured to the end plate 99' 35 of the chamber 95. A rib 119 on this plate 118 has secured thereto the guide flange 120 between which and the plate 118 the rack bar 121 is 40 slideable. This rack bar has its teeth 122 engaged with the aforementioned pinion 110. The rack bar 121 has a cam bar 123 connected thereto in spaced parallel relation, the rib 119 which is preferably in a pair of sections serving as a guide between the same and the rack bar 121. A projection 124 extends laterally from the cam bar 45 123, the cam bar being tapered at one end as at 125 for cooperation with the roller 126 on the rocker 127. This rocker 127 is provided with an upstanding arm 128 connected by a spring 129 to the foot portion 106 of the valve element arm 105. 50

A swingable arm 130 on the flange 120 has its free end connected by a coiled spring 131 to the foot 106 of the valve element arm 105 and is located in the path of the projection 124 on the cam bar 123. 55

A wire spring 132 extends from the anchor 133 to engage into the slot of the screw head 134 on the valve element 100. An elongated articulate shaped detent arm 135 is pivotally supported by the end plate 99' of the chamber 95 as at 136 60 and has at its intermediate portion a pair of shoulders 137 and 138, behind one or the other of which the foot 106 on the valve element arm 105 can engage to communicate one side or the other of the piston in the chamber 95 with the atmosphere while connecting the compartment on the other side of the piston in the chamber 95 with the vacuum supply line. At this point it may be well to explain that in conjunction with the apparatus so far described and hereinafter to be described, a vacuum tank is somewhere employed and supported on the vehicle and a line from this vacuum tank with a shut-off valve therein (not shown) is connected to the fitting 17 on the top of the shell 15. 70 75

It can be seen in Figure 13, that a wire spring 139 is employed and anchored at 140 so that its tension is exerted against the detent arm 135 thus maintaining the arm tensionally urged downwardly against the foot portion 106 of the valve element arm 105.

Obviously, when the arm 105 is in the position shown in Figure 13, the spring 129 is under tension and when the rack 121 is shifted in the opposite direction, the spring 131 is put under tension as shown in Figure 14.

Under certain conditions, it may be necessary to operate the mechanism manually in which instance the fitting 11 or the line thereto will be open to the atmosphere. This manual control consists of a cup shaped member 141 secured to the outside of the end plate 21 of the shell 15. A short shaft 142 is journaled through the bottom of this cup 141 and is provided with an internally toothed socket 143 which protrudes into the shell 15 in opposed relation to the gear 110.

A hand knob 144 is secured to the shaft 142 by a screw 145 or some other suitable securing element, while a coiled compressible spring 146 is interposed between the bottom of the cup-shaped element 141 and the knob 144. Obviously, by forcing inwardly on the knob 144, the internally toothed socket 143 will engage the pinion 110 and by rotating the knob the core 107 and the mechanism it is intended to operate will be actuated.

A description of the annunciator will now be given. It can be seen that an annulus 147 is provided in the shell 15 at the annunciator 39 and through this projects the elongated pin 148 which is engageable with the clapper assemblies as shown in Figure 23. One of these assemblies is shown taken apart in Figure 24.

It will be observed that each of these clapper assemblies consists of a plate 149 secured by a screw or similar means 150 to the annulus 147. This screw 150 also pivotally mounts the rocker 151 on the plate 149. Thus both the plates 149 and the rocker 151 are swingably supported by the annulus 147. Both the rocker 151 and the plate 149 are provided with an ear 152 and it can be seen that coiled springs 153 and 153' extend from anchor points 155 to connect each to one of the ears 152. The plate 149 has an outstanding member 156 provided with a threaded opening to receive the headed screw 157. Numeral 158 represents the clapper having the leg portions of the U-shaped shank 159 projecting therefrom. The legs of this shank 159 straddle the screw 157 and the head can be tightened against the shank to retain the same firmly supported by the outstanding member 156. A stop screw 160 can be employed on the annulus 147 for each of the clapper assemblies so as to limit the return motion of the corresponding plate 149.

In the operation of the machine, it can be seen that the parts will be normally positioned as shown in Figure 4 preparatory to the reception of a coin. When the coin is inserted into the slot 23 (see Figure 4) the slider 66 is forced toward the left. As the pivotal member 75 moves away from the drive pin 38, the spring behind the pivotal member 75 swings the member upwardly so that it goes above the drive pin 38. As the coin goes into the machine, having passed completely through the slot 23, the spring tensioned pinion 49 drives the slide plate 66 back toward the right and as the extension 65 closes off the coin slot the teat 87 strikes the lug 86 and rotates the

shaft on which the lug 88 is located. (See Figure 14). The lifting of this lug 88 elevates the detent arm 135 to such an extent that the shoulder 31 clears the foot member 106, thus permitting the spring 131 to swing this foot and actuate the valve so as to start the suction operating means for actuating the drive pin 38.

Obviously, when the nickel is forced down the passageway by the drive pin 38, the nickel is carrying the collar 47 with it, resulting in the riding of the eccentric slot 58 over the pin 55 so that the collar 47 causes a lifting action of the closure 52, so as to disengage it from the outlet 51, while subsequently, the follower wedge 42 will engage the closure 52 and swing the same, including disk assembly D, away from outlet 51 until the end of slot 64 in assembly disk D, Figure 8, contacts pin 63, which is attached to stationary partition C, thereby preventing disk assembly D, together with closure plate 52 and follower wedge 42, which now is in contact with closure slide plate 52 from further rotating, causing drive pin 38 to eject the nickel through opening 51 as seen in Figure 5. The machine then continues to rotate carrying pin 38 past follower wedge 42 and 25 the machine finishes its stroke in a clockwise direction as shown in Figure 5 at which time adjustable cam (not numbered) on top of and attached to rack 122, Figure 14, rides under and lifts arm 135 releasing valve arm 105, Figure 30, 30 allowing tension of spring 131 to carry vacuum valve to the opposite position, causing vacuum motor and machine to rotate in a counterclockwise direction. Lug 61 of return plate 60 engages pin 58, which extends from collar 47 through slot 35 59 in disk assembly D, causing collar 47 to rotate counterclockwise until pin 58 contacts the end of slot 59, at the same time the end of slot 58 in collar 47 has contacted pin 55, Figure 4, and released closure 52, all of which now are rotated 40 further in a counterclockwise direction by return plate 60 until the end of slot 64 in disk assembly D has contacted pin 63, Figure 8, pin 63 being attached to stationary partition C prevents disk assembly D from rotating further and holds 45 the assembly in the starting position as shown in Figure 8. Closure 52 is caused to enter opening 51 by spring tension thereby closing said opening as seen in Figure 4. Meanwhile drive pin 38 has contacted pawl 75 carrying with it sliding plate 50 66 thereby opening coin slot 23 to the set or starting position as shown in Figure 4.

Of course, in the case of a dime deposit, the drive pin 38 simply drives the dime downwardly in the passageway with the follower 42 riding in 55 advance of the coin, but because of the smallness of the dime, the same escapes the collar 47 and merely rides over the nickel outlet closure 52 and passes to the dime outlet 57 where it is deflected by the wedge-shaped follower 42. Then 60 the adjustable cam (not numbered) on top of rack 122 rides under and lifts arms 135 releasing vacuum valve arm 105, Figure 30, allowing tension on spring 131 to shift vacuum valve 100 to the opposite position, thereby causing vacuum 65 motor and machine to rotate in a counterclockwise direction, until drive pin 38 contacts pawl 75 carrying sliding plate 66 to the open or starting position as shown in Figure 4. The machine is held in the open or starting position by the continuous pull of the vacuum motor until the vacuum valve 100 is tripped by the insertion of another coin.

In the full stroke device 69 and 70 the teeth on slide plate 66 are set to take a coin the diameter of 75

a dime. If a larger coin is inserted the sliding plate 66 carries notch 69 on past catch 70, but as there are no teeth beyond notch 69 the catch 70 simply returns along the sliding plate 66 to notch 69. It can readily be seen that the extra travel of sliding plate 66 when inserting a coin larger than a dime does not effect the proper working of the device.

During this motion of the coin through the coin passageway, as the coin passes over the nickel outlet 51, the pin 148a will operate the register 31 once, through the arm 31a of the register and at the same time the pin 148 passes the first clapper assembly shown in Figure 23 and advancing over this first assembly the first rock of the rocker 151 trips the companion clapper 158 and results in the sounding of the bell 30a. In the case of the dime, this coin continues on through the passageway and by the time the follower 43 reaches the dime outlet 51 (see Figure 7), the pin 148a has moved the arm 31a a sufficient distance farther to again actuate the register 31, making two counts for the dime, while at the same time the pin 148 has passed over the rocker 151 of the second clapper assembly without affecting the associated clapper, but as the mechanism starts to return, the pin 148 will ride back across the rocker 151 of the second assembly and at this time cause the second sound of the bell. As the pin returns to the normal position shown in Figure 23, it does not operate the first clapper again as the rocker thereof will be free to swing and yield to the travel of the pin 148.

In the use of a nickel, the vacuum control means is set off in the same manner, but as the nickel is of greater diameter than the dime, the same will extend completely across the coin passageway. Thus a portion of the nickel will seat itself in the cut-away portion 59 of the collar 47, as shown in Figure 4, and as the drive pin 38 drives the coin downwardly in the passageway, the collar 50 will be caused to follow. In other words the collar 50 will rotate on the hub 34. During this actuation of the collar 50, the edge portion of the same at the eccentric slot 56 therein is riding against the pin 55 of the nickel outlet closure shank and is gradually lifting the closure from the outlet 51 so that it is in a position, by the time the follower 42 reaches it, to be pushed aside by the follower 42 to substantially the position shown in Figure 7. Obviously, the outlet is completely open when the nickel approaches the same and with the pressure of the drive pin 38, the nickel will be deflected by the follower 42 through the open nickel outlet and will fall into the receptacle 8. As the nickel only travels one-half the distance, or substantially one-half the distance that the dime travels, the pins 148a and 148 will not have an opportunity to actuate the register 31 and annunciator 30 a second time. Thus, there will only be one count and one annunciation for each nickel deposited and two counts on the register and a double annunciation for each dime deposited.

It will be observed that the jacket 16 has an opening 16a for the register 31, an opening 16b to accommodate the coin slot plate 19 and an elongated slot 16c in the lower portion thereof to register with the nickel and dime outlet in the bottom of the shell 15. It will also be observed that the jacket 16 is split longitudinally to facilitate application to the shell 15 and it will also be observed that if this jacket is of spring material it will have a tendency to snugly fit the shell 15 and the opposed longitudinal edge por-

tions will be substantially concealed, being located under the shell.

While the foregoing specification sets forth the invention in specific terms, it is to be understood that numerous changes in the shape, size, and materials may be resorted to without departing from the spirit and scope of the invention as claimed hereinafter.

What is claimed is:

1. A coin register comprising a coin counter, a coin passageway, means for actuating the counter at predetermined intervals of distance through which the coin travels in the passageway before discharging, said passageway being provided with outlets at said predetermined intervals, a closure for the first of the outlets so that small coins can pass thereover, and means whereby large coins can remove said closure to permit the discharge thereof.

2. A coin register comprising a casing having a coin slot and a coin path therethrough, coin moving means in said path, a coin counter, separate outlets along said path for large and small coins, a closure for the large coin outlet, means responsive to the passage of large coins for removing the closure and permitting discharge of large coins through said large coin outlet, and means whereby the counter is operated once for a coin discharged through one outlet, and more than once for coins discharged through the other outlet.

3. In a coin depository, a coin passageway, a coin mover in the passageway, a coin follower in the passageway, a large coin outlet and a small coin outlet in the passageway, a closure for one of the outlets, said follower being adapted to open said closure when a coin of predetermined size approaches the adjacent outlet, and annunciating and registering means actuated as a coin passes over the closure or through either outlet.

4. In a coin register, a coin passageway, a coin mover in the passageway, a coin follower in the passageway, a coin counter adapted to be operated by said follower, vacuum means for actuating the said coin mover against the coin, and a reversing valve for said vacuum means whereby the coin mover will be returned to re-set position after a coin has been discharged.

5. In a coin register, a coin passageway, a coin mover in the passageway, a coin entrance for the passageway, a coin outlet for the passageway, a coin mover in the passageway, means for actuating said mover, and a trip adjacent said coin entrance for setting off said means as a coin is forced through the entrance against said trip, said means comprising a vacuum reservoir, a chamber, a piston in the chamber, a conduit between the chamber and the reservoir, and a valve in the conduit controlled by said trip.

6. In a coin register, a coin passageway, a coin mover in the passageway, a coin entrance for the passageway, a coin outlet for the passageway, a coin mover in the passageway, means for actuating said mover, a trip adjacent said coin entrance for setting off said means as a coin is forced through the entrance against said trip, and means for automatically shutting off said entrance until the coin mover returns to re-set position, said means including a slide, a spring drive for the slide, a rack on the slide, and a reversing pawl engageable with the rack.

7. In a coin register, a coin passageway, a coin mover in the passageway, a coin entrance for the passageway, a coin outlet for the passageway, a coin mover in the passageway, means for

actuating said mover, a trip adjacent said coin entrance for setting off said means as a coin is forced through the entrance against said trip, and means for automatically shutting off said entrance until the coin mover returns to re-set position, said means including a slide, a spring drive for the slide, a rack on the slide, and a reversing pawl engageable with the rack, said coin mover being adapted to actuate the slide to partly open position when it returns to re-set position.

8. In combination, a casing having a cylinder in one end thereof, an annunciator in the opposite end of the casing, a piston in the said cylinder, means for actuating the said piston, said casing having a coin passageway therethrough, a coin mover in the passageway, a drive connec-

tion between the piston and the coin mover, a coin follower, said coin follower being adapted to actuate the said annunciator.

9. In combination, a casing having a cylinder in one end thereof, an annunciator in the opposite end of the casing, a piston in the said cylinder, means for actuating the said piston, said casing having a coin passageway therethrough, a coin mover in the passageway, a drive connection between the piston and the coin mover, a coin follower, said coin follower being adapted to actuate the said annunciator, and a register in the second-mentioned end of the casing adapted to be actuated by the follower simultaneously with the annunciator.

GEORGE B. DUNN.
